CLAIM

The ornamental design for an acorn-shaped speaker and radio, as shown and described.

DESCRIPTION

FIG. 1 is a front elevational view showing the acorn-shaped speaker and radio;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a front perspective view thereof.

The broken lines are for illustrative purposes and form no part of the claimed design.
